INCANDESCENT ANODE LAMP

Charles Francis Jenkins, Washington, D. C., assignor to Jenkins Laboratories, Washington, D. C., a corporation of the District of Columbia

Application June 13, 1928. Serial No. 285,014

17 Claims. (Cl. 176—122)

This invention relates to gaseous glow lamps, and has for its principal object a lamp more responsive to radio than lamps heretofore available.

5 Another object is to reduce the voltage required to light the glow targets.

Still another object is to effect the lighting of the targets with less control voltage.

Applicant shows in a copending case, Serial 10 No. 113,266, a multiple cathode lamp with means for lighting the cathode targets in succession. The gaseous content of this lamp is selected for the best results under given circumstances. Among these circumstances is the voltage required for the particular gas employed. It has been found that a hot electron stream between the anode and the cathode of such a lamp greatly decreases the voltage necessary to light the targets.

20 It has also been discovered that a change in the current flow between anode and cathode can be controlled by the establishment of an opposing field in the neighborhood of the stream.

With this and other objects in view, the invention consists of the novel combination of parts herein described, illustrated in the drawing, and more particularly pointed out in the claims.

In the drawing, A is a lamp body, filled with 30 a low voltage gas, neon, for example; B, B, B, B are cathodes; C an anode which can be brought to incandescence or other state which will supply an electron stream between anode and cathode; D is a circuit terminal by which an opposing field can be set up to effect the current flow between anode and cathode.

The cathode targets, the anode, and the grid, all have wire leads as shown at E.

In use, two of these leads supply current to 40 the anode filament to make it glow; while a single terminal to each of the other elements is sufficient.

It is well known in the gaseous glow lamp art that under conditions of proper spacing and 45 gas pressure, cathode targets can be made to glow with sufficient intensity, and with sufficient rapidity of change to make them adaptable to radio vision and radio movies. This is the purpose for which applicant is using such 50 lamps.

However, under the best arrangement of elements, and of gas pressure, the lamp still requires quite a high voltage to break down the resistance between anode and cathode and make 55 the cathode glow. Such high voltages are not

desirable in machines which may come into use by children or others unfamiliar with the risk involved in such high voltages.

It has been found that this high voltage can be very materially reduced by establishing a hot 60 space or other low voltage path between anode and cathode.

It has also been found that the current flow in such a field is easier controlled by setting up a controlling field in the neighborhood of this 65 hot space, as, for example, by applying a potential near thereto, as at D.

In operation, therefore, current is applied to the anode to bring it up to an incandescent state; a potential is also set up between the 70 anode and the cathode, though much lower than that required to make the cathode glow in the usual type of lamp. A modulating control voltage is then applied to the wire E to oppose the current flow between anode and cathode, so 75 that the cathode target ceases to glow. This control is equally applicable, of course, to all of the targets shown.

It will also be understood that instead of an opposing field, a boosting field may be established between anode and cathode by the use of circuit terminal E, and naturally I do not wish to limit myself to either the one or the other action. Thus the electrode D may be rendered either positive or negative with respect to the 85 anode C, as is found desirable.

What I claim, therefore, is—

1. In gaseous-glow lamps, the combination of a plurality of cathodes having separate terminals, and an incandescent anode providing low 90 voltage paths to said cathode, and a control circuit established in proximity to said anode-cathode space, the whole enclosed in an atmosphere of low voltage gas.

2. In gaseous-glow lamps, the combination of 95 a plurality of cathodes having separate terminals, an incandescent anode common to all the cathodes, and a control circuit established in proximity to said anode-cathode space.

3. In a gaseous glow lamp the combination of 100 a plurality of similar separate electrodes and two other electrodes each common to all of said separate electrodes, the first of said other electrodes serving to provide discharge paths to each of said separate electrodes, the second of 105 said other electrodes being incandescent and serving to control the field in each of said paths of all said electrodes being enveloped in a conducting gas.

4. In a glow discharge lamp a plurality of sep- 110

- arate cathodes arranged in row formation, an anode extending before each of said cathodes, and a discharge controlling electrode also extending past each of said separate electrodes.
5. In a glow discharge lamp the combination of a plurality of separate electrodes arranged in row formation, another electrode extending past each of said separate electrodes, and an incandescent electrode also extending past each of said separate electrodes.
10. 6. In combination a cathode, an incandescent anode for said cathode, and a control electrode situated to control the electron stream between said anode and cathode.
15. 7. In combination a first electrode, a second electrode, a source of potential connected across said electrodes to cause one electrode to act as an anode and the other as a luminous cathode, means for rendering said anode incandescent, and means for varying the intensity of illumination of said cathode.
20. 8. The combination according to claim 7, in which the means for varying the luminosity of the cathode includes a third electrode positioned to control the discharge between the anode and cathode.
25. 9. A lamp comprising an incandescent electrode, another electrode, means for producing a luminous discharge on one of said electrodes, comprising an envelope for enclosing said electrodes in a conducting gas, and a source of potential connected across said electrodes, said gas being at such a pressure and said potential being of a value to confine the luminous discharge substantially entirely to a cathode glow.
30. 10. A lamp according to claim 9 in which said other electrode is in the form of a plate.
35. 11. A lamp according to claim 9 in which the incandescent electrode serves as the anode and the said other electrode serves as the cathode.
12. A lamp according to claim 9 in which the gas pressure and voltage are so chosen as to 80 confine the cathodic glow substantially entirely on said other electrode.
13. A lamp according to claim 9 in which a third electrode is provided for controlling the luminosity of said one of said electrodes. 85
14. A cathode glow lamp comprising an incandescent electrode, another electrode mounted in spaced relation to the incandescent electrode, and means for causing said lamp to emit light consisting substantially entirely of cathodic 90 glow comprising means for enclosing said electrodes in an atmosphere of a conducting gas, and a source of potential connected across said electrodes.
15. A cathode glow lamp according to claim 95 14 in which the enclosing atmosphere for the electrodes contains neon.
16. The method of operating a cathode glow lamp of the type having an incandescent anode, which comprises subjecting the discharge between the anode and cathode of said lamp to an electric field and varying said field in accordance with electric signals to correspondingly vary the intensity of the cathode glow. 100
17. In combination a cathodic glow lamp having a pair of electrodes, the anode of which is incandescent, means for subjecting the discharge between said electrodes to an electric field, and means for varying said field in accordance with electric signals to correspondingly 110 vary the intensity of the cathode glow. 105
